CLAIM

The ornamental design for a cutting tool having a plurality of cutting blades, as shown and described.

DESCRIPTION

FIG. 1 is a perspective view of a cutting tool having a plurality of cutting blades illustrating our new design; FIG. 2 is a side elevation view of the cutting tool having a plurality of cutting blades;

FIG. 3 is a similar side elevation view, with the cutting tool having a plurality of cutting blades rotated about 180 degrees;

FIG. 4 is a top plan view of the cutting tool having a plurality of cutting blades; and,

FIG. 5 is a bottom plan view of the cutting tool having a plurality of cutting blades.

FIG. 1

FIG. 2

FIG. 3

FIG. 4

FIG. 5
